(57) **CLAIM**

The ornamental design for a standing tape dispenser, as shown and described.

DESCRIPTION

FIG. 1 is a bottom left front perspective view of the standing tape dispenser according to our new design;

FIG. 2 is a bottom right rear perspective view thereof;

FIG. 3 is a top front left perspective view thereof;

FIG. 4 is a top right rear perspective view thereof;

FIG. 5 is a left elevational view thereof;

FIG. 6 is a right elevational view thereof;

FIG. 7 is a front elevation view thereof;

FIG. 8 is a rear elevation view thereof;

FIG. 9 is a bottom plan view thereof; and,

FIG. 10 is a top plan view thereof.

The broken lines shown in the drawings form no part of the claimed design.
